UNITED STATES PATENT OFFICE

CHARLES L. RAYFIELD, OF CHICAGO, ILLINOIS, ASSIGNOR TO RAYFIELD MFG. CO., OF CHICAGO, ILLINOIS, A CORPORATION OF ILLINOIS

OIL BURNER FEED MECHANISM

Application filed December 26, 1929. Serial No. 416,392.

My invention relates to a method of and apparatus for pumping fluid such as fuel to oil burner nozzles and the like.

One of the important objects of the invention is to utilize a pump structure of the angular rotary type in which sets of interconnected plungers disposed at right angles to each other to operate consecutively to propel fluid in a constant regular stream without any check or momentary interruption to the flow for use in pumping a multi-fluid stream such as atomized fuel used in an oil burner.

Another important object of the invention is to utilize one of the pump sections of the pump structure for pumping fluid into a supply source and the other pump section for pumping the fluid from the supply source and delivering it to the place of consumption.

A further important object of this invention is to utilize one of the pump sections of the type of pump structure referred to for circulating combustion fluid to and from a supply source, and utilizing the other pump section for receiving a part of this circulating combustion fluid and mixing air under pressure therewith to cause atomization of the fluid and to form a good combustion mixture to be delivered to a source of consumption such as an oil burner nozzle.

Another object of my invention is to provide a fuel pumping system in which oil discharged from a pump is utilized for lubricating and sealing purposes in connection with both the pump and a compressor prior to the combination of the oil with compressed air for atomizing the oil.

A further object is to utilize one of the pump sections of the pump structure for pumping combustible oil and adapting the other pump section of the structure for receiving the pumped oil and for causing atomization thereof by mixing compressed air therewith in order to form a combustion mixture to be delivered by this construction to a source of supply such as a burner nozzle in an oil burner system.

A still further object is to utilize the pump structure as a two step compressor, one pump

section subjecting a fluid to a preliminary compression and the other pump section receiving and subjecting the fluid to a final compression before delivery thereof from the pump structure.

Another important object of the invention is to utilize one of the pump sections of the pump structure for forcing the oil under pressure through the pump structure housing in order to seal and lubricate the plungers and the rotary cylinders, and to hold to their seats the rotary cylinders which control the flow of fluid through the pump structure.

The above and other features of the invention are incorporated in the structure disclosed on the drawings in which Figure 1 is a side elevational view of the rotary angular pump structure.

Figure 2 is a sectional view on plane II-II, Figure 1.

Figure 3 is a side elevational view with the rotary cylinder and enclosing housing in vertical diametrical section.

Figure 4 is a section on line IV-IV of Figure 3.

Figure 5 is a view on plane V-V, Figures 1 and 3, and

Figure 6 is a diagrammatic view showing the connection of the pump structure in service for supplying combustion fuel for a combustion device such as an oil burner.

The pump structure comprises the cylindrical housing 10 and 11 detachably secured together at their inner ends along a plane of 45° by means of their flanges 12 and 13 and screws 14, the housing being thus at a right angle with each other. A head 15 is applied to the outer end of the housing 10 and is detachably secured thereto by means of screws 16 passing through the head flange 17 and the flange 18 on the housing. A head 19 is applied to the outer end of the housing 11 and is detachably secured thereto by screws 20 passing through the flange 21 on the head and engaging in the flange 22 of the housing.

At the juncture of the housings 10 and 11 is the chamber 23 and between this chamber and the head 15 is the rotary cylinder 24.

which is confined axially between the top surface of the head and the bevelled annular flange or shoulder 25. The cylinder has a plurality of cylindrical bores 26 extending longitudinally therethrough. Four such bores are shown regularly spaced about the cylinder axis, and reciprocable in each bore is a plunger 27. The lower end of the cylinder is closed by a wall 28 having ports 29, one for each bore. Extending axially from the wall 28 is a cylindrical stub 30 which engages in the upper end of the bore 30' of the head 15. The cylinder 24, the wall 28 and the stub 30 may be part of an integral casting, or as shown the stub may be integral with the wall 28 and the wall secured to the cylinder as by means of the threaded stud 31.

Within the housing 11 is the rotary cylinder 32 which seats at its outer end against the head 19 and engages at its upper end against the bevelled annular shoulder 33. Like the cylinder 24, this cylinder 32 has four longitudinal bores 34 in each of which engages a plunger 35. The cylinder has the outer wall 36 which may be integral therewith or secured thereto as by means of a threaded stud 37, and extending axially from the wall is a shaft 38 which journals in the head 19 and projects therefrom for the attachment thereto of a suitable driving motor (not shown). The wall 36 has the ports 39, one for each of the bores 34.

The plungers in the corresponding bores of the two cylinders are rigidly connected together at their outer ends as by means of an angular web 40 so that when the shaft 38 and the cylinder 32 connected therewith are rotated, the angular plunger structures will reciprocate in the bores of the two cylinders 24 and 32 and will also partake of bodily movement and will transmit the rotation of the cylinder 32 to the cylinder 24, all in a manner well understood in the art.

The head 15 has at one side a radially extending inlet passageway 41 adapted to be connected by suitable piping 42 with an oil supply reservoir (not shown). From this inlet passageway a port passageway 43 extends through the head and terminates at the upper face thereof in an arcuate channel 44 concentric with the axis of cylinder 24 and in the path of the ports 29 in such cylinder. At the opposite side the head has the outlet passage 45 from which extends a port passageway 46 to the upper face of the head and there terminates in the arcuate channel 47 which is also in the path of the cylinder ports 29. These channels 44 and 47 are not quite semi-circular but their ends are separated by spaces 48 and 49 whose width is equal to or slightly greater than the diameter of the cylinder ports 29. During each rotation of the cylinder 24 each of its plungers will make a complete back and forth stroke in the respective bore and during the inward

stroke of each plunger the associated port 29 will be in register with the inlet channel 44, and during the outward stroke of such plunger the port will be in communication with the outlet channel 47. At the end of each stroke of the plunger its associated port will be closed by either of the spaces 48 and 49 between the ends of the channels. The plungers operate consecutively and during the inward strokes fluid will be drawn into the respective bores through the inlet channel 44, and during the outward strokes such drawn in fluid will be expelled through the outlet channel 47 and to the head outlet passage 45 from where it may be conducted by suitable piping 50.

In the head 19 the arrangement is similar to that in the head 15. The inlet passage 51 has a port passage 52 extending therefrom and terminating in the face of the head 19 in the arcuate channel 53 disposed in the path of the ports 39 of cylinder 32. The outlet passage 54 is connected by port passageway 55 with the arcuate channel 56 in the face of the head 19, this channel being also in the path of the ports 39 and the channels being separated by the spaces 57 on the head face. The plungers in cylinder 32 operate consecutively and in unison with those of cylinder 24 and during the in stroke of a plunger its associated port will be in communication with the inlet channel 53 and during the out stroke the port will be in communication with the outlet channel 56. The fluid is thus drawn into the cylinder bores from the inlet 51 and discharged therefrom into the outlet 54.

The housing 10 has a longitudinal boss 58 one side through which extends the passageway 59 which is connected at its lower end with the outlet passageway 45 by way of the port passage 60 through the head 15. At its upper end this passage 59 communicates with the chamber 23 at the junction of the housings 10 and 11.

The housing 11 has a longitudinal boss 61 through which extends a passageway 62 which communicates at its lower end with the inlet passageway 51 by way of the port passage 63 in the head 19. The passageway 62 communicates at its upper end with a lateral inlet passage 64 which may be connected directly by piping 65 with the chamber 23 in the pump structure housing. Designating the two pump sections of the pump structure as P and P', it will be noted that the pump section P, when pumping oil, will deliver it by way of the chamber 23 to the inlet of the pump section P', the oil flowing from the outlet 45 of the pump section P through passageway 59, chamber 23, pipe 65, and passages 64, 62 and 63 to the inlet end 51 of the pump section P'. When the oil is under pressure it will fill the chamber 23 and will form a seal for the plungers, and the pressure against the cylinders will hold them against their seats

on the heads 15 and 19 respectively so as to prevent leakage. The oil will also lubricate the plungers and the cylinders and will reduce friction to a minimum.

5 When the pump section P is directly connected with the pump section P', the fluid will first be put under pressure in the pump section P', and the fluid will then be delivered through suitable piping 66 to the source of consumption. Such consumption source might be the burner or nozzle of an oil burning system and in that case provision would preferably be made to supply air to the pump structure P' to be compressed therein and thoroughly mingled with the fluid under compression so that the fluid, in this case oil, would be thoroughly atomized and aerated before delivery to the burner. In Figure 4 I have shown an air intake 67 through which air may be drawn into the pump section inlet passage 51 to mingle with the oil flowing into said inlet from the passageway 62. Provision may be made to adjust for the pressure of the fluid delivered by the pump section P to the pump section P' and in Figure 2, I have shown the outlet piping 50 of the pump section P to include an automatically controlled check valve 68 through which fluid will be by-passed back to the fluid supply reservoir when the pressure of the pumped fluid tends to rise above a certain predetermined amount. Under such arrangement the pressure of the fluid delivered by the pump section P to the pump section P' will be kept constant.

35 Instead of having the pump section P deliver directly to the pump section P' it could be connected to deliver first to an auxiliary tank 69 as shown in Figure 6 and this tank may be of the type disclosed in copending application Serial No. 273,497, filed April 28, 1928, in which a float controlled valve shuts off the fluid inlet as soon as the fluid reaches a predetermined level. In Figure 6, I have shown the pipe 65 connected from chamber 23 with the inlet of the auxiliary tank instead of directly with the pump section P', and the tank outlet is connected by pipe 70 with the inlet 64 of the pump section P' so that the fluid will be delivered first to the auxiliary tank and then drawn therefrom by the pump section P' to be mixed with air entering the air intake 67, the air being then compressed and the fluid, in this case oil, being thoroughly atomized and aerated under pressure before delivery to the burner. I have shown supporting structure 71 for the auxiliary tank, and the pump structure can also be mounted on said support as by means of a stud 72 threaded into the outer end of the bore 30' in the head 15.

60 In the rotary angular pump structure utilized, the plungers reciprocate successively rapidly and with perfect regularity so that the fluid or mixture delivered is in a constant regular stream without any check or momen-

tary interruption to the flow, and as the pump section P' draws from a constant head in the auxiliary tank 69, the delivery pressure will be uniform and constant. The pump structure also lubricates itself under pressure and keeps itself sealed against leakage.

65 In Figure 6, I have shown a valve 73 included in the intake pipe 70 for the pump structure P'. This valve may be electromagnetically or otherwise automatically controlled to shut off partly or wholly the fluid intake by pump P'. Of course, upon closure of the valve 73, the tank 69, as soon as it is filled to normal level, will be closed by its float controlled valve to further inflow from the pump section P, and the delivery from said pump section will then be diverted back to the main reservoir through the check valve 68 which may be spring controlled.

70 It is evident that my improved pump structure may be used to advantage as a two-step compressor for compressible fluids such as air, the fluid being subjected to initial compression in one of the pump sections and then to increased or final compression in the other pump section. Incompressible fluids such as liquids would be given an initial pressure head in one of the pump sections and an increased or final pressure head in the other pump section. One way of using my 75 pump as a two stage compressor would be to use larger bores in the first pump section than in the second section and another way would be to use less cylinder bores in the second section than in the first so that the 80 second section has lesser volume for air than the volume of the compressed air leaving the first pump section.

75 The pump structure, on account of its simplicity of construction and operation and the 85 elimination of all valves or other delicate parts, is particularly adaptable for use in oil burner systems.

80 While I have shown and described my invention in a preferred form, changes and 90 modification in structure and arrangement may be made without departing from the spirit and scope of the invention and I therefore, do not limit my invention except as 95 specified in the appended claims.

110 I claim as follows:

1. In a pump structure of the class described, the combination of a housing comprising two cylindrical sections secured together at an angle with each other, a cylinder 115 in each section rotatable therein, driving means connected with one of said cylinders, said cylinders having corresponding longitudinal cylindrical bores, pairs of plungers joined at their outer ends and reciprocable in corresponding bores of said cylinders for translating the rotary movement of the driven cylinder into corresponding rotary movement of the other cylinder, a head for each section closing the end thereof and 120

- forming a seat for the respective cylinder, each head having a fluid inlet and a fluid outlet terminating respectively in inlet and outlet ports in the face of the head, each cylinder having a port for each bore, said cylinder ports consecutively communicating with the inlet and outlet ports of the respective head when the cylinder is rotated whereby fluid is consecutively drawn from the head inlet 5 into the bores by the plungers and expelled therefrom through the head outlet, and a fluid connection between the outlet of one head and the inlet of the other, the interior of said housing being included in said connection.
- 10 2. In a pump structure of the class described, the combination of a housing comprising two cylindrical sections disposed at an angle with each other, a cylinder rotatable in each section and one of said cylinders being adapted to be connected with driving means, said cylinders having corresponding cylindrical longitudinal bores, pairs of plungers joined at their outer ends and reciprocable 15 in corresponding bores of said cylinders for translating the rotary movement of the driven cylinder into corresponding rotary movement of the other cylinder, a fluid inlet passageway and a fluid outlet passageway at 20 the end of each section terminating in inlet and outlet channels adjacent to the outer ends of the bores of the respective cylinders, the bores of each cylinder consecutively communicating alternately with said inlet and 25 outlet channels as the cylinder rotates whereby fluid is pumped from the inlet passageway into the outlet passageway of each section, a chamber in said housing adjacent to the inner ends of said cylinders, and a fluid 30 connection between the outlet passage of one of said sections and said chamber.
- 35 3. A fluid pump structure comprising two rotary pump sections having their axes at an angle with each other, each section comprising a stationary cylindrical housing, a cylinder rotatable in each housing and having a plurality of longitudinal cylindrical bores therein regularly spaced around the cylinder axis, one of said cylinders being adapted to be 40 driven, pairs of plungers joined at their inner ends and engaging in corresponding bores of said cylinders for transmitting the rotation of the driven cylinder to the other cylinder, a head for each pump section forming 45 a seat for the cylinder therein, a fluid inlet passageway and a fluid outlet passageway in each head, said passages terminating in intake and outlet ports respectively for alternate communication with the successive bores of the 50 associated cylinder as the cylinder is rotated, each bore communicating during the in stroke of its plunger with the inlet port and with the outlet port during the out stroke of its plunger whereby the plungers of each pump structure will successively induct fluid from the 55

corresponding head inlet passage and discharge the fluid through the head outlet passage, a chamber connecting the inner ends of said housings for holding fluid under pressure a connection for the flow of fluid from the discharge passage of one of said pump sections to said chamber, said chamber having an outlet, and a connection for conducting fluid from said outlet to the inlet of the other pump section. 70

4. A pump structure for pumping combustible oil comprising two rotary pump sections having their axes at an angle with each other, each section comprising a stationary cylindrical housing, a cylinder rotatable in each housing and having a plurality of longitudinal cylindrical bores therein regularly spaced around the cylinder axis, one of said cylinders being adapted to be driven, pairs of plungers joined at their inner ends and engaging in corresponding bores of said cylinders for transmitting the rotation of the driven cylinder to the other cylinder, a head for each pump section forming a seat for the cylinder therein, an inlet passage and an outlet passage in each head, said passages terminating in intake and outlet ports respectively for alternate communication with the successive bores of the associated cylinder as the cylinder is rotated, each bore communicating during the instroke of its plunger with the inlet port and with the outlet port during the out stroke of its plunger whereby the plungers of each pump structure will successively induct oil from the corresponding head inlet passage, and discharge the oil through the head outlet passage, a chamber connecting the inner ends of said housings, a connection for the flow of oil from the discharge passage of one of said pump sections to said chamber, said chamber having an outlet, and a connection for conducting oil from said outlet to the inlet of the other pump section, said other pump section having an air inlet for the intake of air together with the oil to be compressed in said pump section and to mix with and atomize the oil before delivery of the oil from said pump section outlet. 90

5. In a fluid pumping device an angular pump construction comprising sets of connected pistons, the pistons of each set being disposed at an angle to each other, housing means including angular legs to define cylinders for said pistons, and a chamber at the junction of said legs, and means for conveying the fluid discharge from one leg through said chamber to enable said fluid to act as a sealing medium for said sets of pistons. 105

6. In a fluid pumping device an angular pump construction comprising sets of connected pistons, the pistons of each set being disposed at an angle to each other, housing means including angular legs to define cylinders for said pistons, and a chamber at the junction of said legs, means for conveying the 120

fluid discharge from one leg through said chamber to enable said fluid to act as a sealing medium for said sets of pistons, and means for thereafter combining said fluid with the fluid acted upon by the pistons in the other leg of the pump.

7. In a fluid pumping device, an angular pump construction comprising sets of integral pistons disposed at an angle to each other, housing means including angular legs to define cylinders for said pistons and a chamber communicating with the inner ends of said cylinders, said pistons during operation moving into said chamber, means for delivering fluid to one leg of said housing, and means for conveying the fluid from said leg to the other leg of said housing, the path of said fluid being through said chamber wherein said fluid serves to lubricate and seal said cylinders and pistons.

8. In a fluid pumping device, an angular pump construction comprising sets of integral pistons disposed at an angle to each other, housing means including angular legs to define cylinders for said pistons and a closed chamber communicating with the inner ends of said cylinders, seats associated with the outer ends of said cylinders, means for delivering fluid to one leg of said housing, and means for conveying said fluid after compression in said leg to the other leg of said housing, the path of said fluid being through said chamber wherein said fluid acts upon the inner ends of the cylinders in such a manner as to force the cylinders outwardly against their seats.

In testimony whereof I have hereunto subscribed my name at Chicago, Cook County, Illinois.

CHARLES L. RAYFIELD.
